UNITED STATES PATENT OFFICE

125,931

DESIGN FOR A COMBINED COSMETIC APPLICATOR AND FACE PATTER

Marion Schermerhorn Fort, Philadelphia, Pa.

Application May 24, 1940, Serial No. 92,554

Term of patent 14 years

To all whom it may concern:

Be it known that I, Marion Schermerhorn Fort, a citizen of the United States, residing at Philadelphia, in the county of Philadelphia and State of Pennsylvania, have invented a new, original, and ornamental Design for a Combined Cosmetic Applicator and Face Patter, of which the following is a specification, reference being had to the accompanying drawing, forming part thereof.

Fig. 1 is an elevational view of a combined cosmetic applicator and face pitter embodying my new design;

Fig. 2 is a vertical edge view thereof;

Fig. 3 is a front elevational view of the handle and applicator-bag-holding portions with the cosmetic applicator bag removed, showing the article as used as a face pitter and cream and lotion applicator;

Fig. 4 is an elevational view of one side of the cosmetic bag shown in Figs. 1 and 2, with the ribbon omitted for convenience of illustration;

Fig. 5 is a cross-sectional view taken on line 5—5 of Fig. 3; and

Fig. 6 is a cross-sectional view on line 6—6 of Fig. 3.

I claim:

The ornamental design for a combined cosmetic applicator and face pitter, substantially as shown and described.

MARION SCHERMERHORN FORT.
